UNITED STATES PATENT OFFICE.

KARL SCHMID, OF LANDSBERG-ON-THE-WARTHE, GERMANY.

SINGLE-ACTING, CONDENSING, CONTINUOUS-CURRENT STEAM-ENGINE.

1,227,836.

Specification of Letters Patent. Patented May 29, 1917.

Application filed July 27, 1914. Serial No. 853,410.

To all whom it may concern:

Be it known that I, KARL SCHMID, manufacturer, subject of the Emperor of Germany, residing at Landsberg-on-the-Warthe,

5 Germany, have invented certain new and useful Improvements in Single-Acting, Condensing, Continuous-Current Steam-Engines, of which the following is a specification.

10 The present invention relates to a single-acting condensing continuous current steam engine, and in particular to engines of this kind of a vertical type, as they are chiefly used as marine engines, for driving dynamos 15 and the like purposes. The object of the present invention is to provide as compact a design as possible, to avoid all piping between engine and condenser and to prevent that the condensate, which is produced, 20 chiefly in starting, penetrates into the crank casing and there, when immersion lubrication is employed, saponifies the oil, whereby also the danger exists that the mixture of oil and condensate gets into the exhaust passage, soils the condenser and renders the condensate unsuitable for feeding the boiler.

This object is obtained, as far as multiple cylinder sets are concerned, essentially by 25 the arrangement that the exhausts of all cylinders open into a common condenser chamber, by the engine frame serving at the same time as condenser casing acting as connection between the cylinders. When this arrangement is provided with continuous current steam engines with closed and evacuated crank casing, the entrance of the condensate into the latter is prevented by the piston being stepped and working with its 30 two steps in a non-continuous, likewise stepped cylinder, whereby the upper end of the smaller cylinder projecting into the exhaust chamber is encircled cup-like not only by the lower end of the larger cylinder projecting into the same chamber but also by the larger end of the piston itself.

In the accompanying drawing a constructional form of the present invention is exemplified.

35 Figure 1 is a vertical section through one cylinder of a single acting continuous current steam engine.

Fig. 2 is the upper portion of a four cylinder engine shown partly in section, seen 40 from one side.

Fig. 3 is a diagram, in a reduced scale, of the plan of a four cylinder engine, the dot-and-dash line II—II indicating the line on which the section in Fig. 2 is made.

And Fig. 4 is a part of a view similar to Fig. 1 of a modified form of condenser chamber provided with spray cooling.

The frame *a* of the engine is constructed in its upper part in form of a condenser chamber *b*, which, in case of a surface condenser is fitted with cooling pipes *c* through which the cooling medium travels in the direction indicated by the arrows. It is obvious that the condenser may also be constructed as injection condenser in which case injectors, sprays or the like would be substituted for the cooling pipes *c*, (see Fig. 4).

The cylinders *d*, which are made in form of ordinary flanged tubes, project with their lower edge *e* so far into the condenser chamber, that the upper edge *f* of each piston, when the latter is in its lowermost position, enters into the condenser chamber. The cylinders *d* are secured to the condenser chamber *b* by means of their flanges *g* only, so that the cylinders can expand freely without any trouble being caused thereby. In the lower part the cylinders communicate with the condenser chamber, several rows of bores being arranged in the present exemplification over each other, the said bores *h* arranged at an angle to the axis of the cylinder which is favorable to the impinging on the cooling surfaces. For avoiding an ineffective exhaust angle, the communications between cylinder and condenser may be bored wholly or partly at right angles to the axis of the cylinder immediately above the piston when in its lowermost position.

The pistons *i* are made as stepped plungers and are guided in cylindrical guides *k* which are disposed partly in the engine frame *a*, partly in the condenser *b*. The upper edge *l* of the cylindrical guides *k* projects for some distance into the lower end of the corresponding cylinder *d* and the upper part of the piston *i* is made at *m* in form of a cuff, so that when the piston is in its lowermost position the upper edge *l* of the guide *k* is overlapped by the head of the piston as seen in Fig. 1. The consequence of such arrangement is, that the condensate, which accumulates either at the lower edge *e* of the cylinder or at the lower edge of the piston head will drip directly into the con-

denser or into the exhaust chamber, while the working surfaces between the lower part of the piston *i* and the cylindrical guide *k* is not reached by the condensate, and the latter can neither penetrate into the crank casing *n* closed all around and serving as oil vessel, and preferably evacuated.

All other parts of the engine have no relation to the subject matter of the present invention and have, for such reason, been either quite omitted or have been only diagrammatically shown and shall not be described any further.

I claim:

15. 1. A single-acting condensing steam engine, comprising a condensing chamber, a working cylinder and a coaxial guiding cylinder extending into said condensing chamber from opposite sides thereof with open inner ends separated from each other; a working piston fitted to said working cylinder, and a rigidly united guiding piston fitted to said guiding cylinder; said working cylinder having exhaust ports leading into the condensing chamber, and said working piston having a longitudinally extended cuff which surrounds the end of the guiding cylinder when the working cylinder is exhausting.
20. 2. A single-acting condensing steam engine, comprising a condensing chamber, a working cylinder and a coaxial guiding cylinder extending into said condensing chamber from opposite sides thereof with open inner ends separated from each other; a working piston fitted to said working cylinder, and a rigidly united guiding piston fitted to said guiding cylinder; said working cylinder having exhaust ports leading

into the condensing chamber, and said working piston having a longitudinally extended cuff which surrounds the end of the guiding cylinder when the working cylinder is exhausting; the working cylinder being of larger diameter than the guiding cylinder, and the open ends of said cylinders being longitudinally overlapped, so that the cuff on the working piston remains within the working cylinder when surrounding the end of the guiding cylinder.

3. A single-acting condensing steam engine, comprising a common condensing chamber, a series of single-acting working cylinders all having open inner ends projecting into the common condensing chamber and constructed with exhaust ports communicating with said chamber, a coaxial guiding cylinder for each working cylinder, each having an open inner end projecting into the condensing chamber from the side opposite to its working cylinder, and each being of smaller diameter than and telescoping partially with its working cylinder, and a working piston for each working cylinder, having a rigidly united guiding piston fitted to the corresponding guiding cylinder; each working piston being constructed with a longitudinally projecting cuff in position to surround the end of the guiding cylinder when the working piston is in the exhaust position.

In testimony whereof the foregoing specification is signed in the presence of two witnesses.

KARL SCHMID.
